SUMP PUMP AND FLOOD CONTROL EQUIPMENT
Axel L. Nielsen, 1316 E. Elza, Hazel Park, Mich.
Filed Mar. 26, 1958, Ser. No. 724,193
14 Claims. (Cl. 200—83)

The present invention relates to improvements in electrically operated sump or flood control pumps, for either rural or urban installation and more particularly to novel and improved provisions whereby the commencement and termination of the operation of the pump are rapidly and reliably controlled under all possible operating conditions to be encountered. The invention provides a pump control whose operation is based on the response of a special multiple diaphragm unit to three pressure conditions, i.e., to the hydrostatic head in starting, to the pump pressure at its discharge duct and to the operating vacuum at its intake.

This application is a continuation-in-part of my pending applications Serial No. 684,111 and Serial No. 684,308, both filed September 16, 1957, of which the former is now Letters Patent No. 2,922,854 of January 26, 1960.

It is a general object of the invention to provide a control for the operating motor of either a pump impeller installed in a sump or one fitted in a sewer riser as an anti-flood precaution. In either case the control embodies a switch and a multiple-diaphragm, pressure responsive unit to govern the making and breaking of a motor circuit at the switch in response to the three pressure factors mentioned above, or a combination of them.

In accordance with another object, pressure and vacuum chambers defined by the multiple diaphragm unit of the control are respectively in static pressure communication with the pump adjacent its hydraulic intake, at its discharge and at its impeller eye.

This enables the control to most rapidly and efficiently respond to all sump or sewer flooding conditions. Static pressure of course controls the initial closing of the motor switch and starting of the pump. If operating under a high head, it is desirable to use the pump discharge pressure to keep the switch closed and insure continued pumping.

On the other hand, in low head operation intake suction operation of the diaphragm unit better performs this function as vacuum at the impeller intake eye increases. Either condition may be the major factor in the operation of the diaphragm, and both may be in effect at the same time, once the pump is started.

In respect to the vacuum control aspect of the invention, it is an object to improve the effect of the vacuum for its intended purposes, in a multiple diaphragm installation as described. This is accomplished by providing improved means for pressure-interconnecting the vacuum control chamber of the unit, defined by a pair of opposed diaphragms, with another chamber of the unit, also in part defined by a diaphragm. The result is that the effect of the vacuum in the first named chamber to move one of the diaphragms thereof in a given direction is overcome or overbalanced by the effect of the equal vacuum in the other chamber of moving its diaphragm in the opposite direction. This intensifies the vacuum-responsivity of the multiple diaphragm unit as a whole.

A further object is to provide a control which is freed from reliance on a float or other mechanical switch operating device as the result of its actuation, as above described, solely in response to various pressure conditions imposed on its multiple diaphragm unit.

In accordance with a still further and more specific object of the invention, the control of cut-in and cut-out of the pump motor may be governed by adjustably vary-

2

ing the spacing of the motor switch from the diaphragm unit which controls its closing and opening.

Another specific object of the invention, particularly in an embodiment of its principles as applied to a sump pump, is a control unit of very simple compact and inexpensive sort which may be supplied as a part of an original sump pump assembly or may optionally be supplied as an adapter type motor control easily and quickly applied to an existing sump pump to afford perfect control of its motor. In either sort of installation the unit has the important advantage that, although it is hydraulically connected to the pump, it need not be physically supported by the pump; nor need it be submerged in the sump.

A further specific object, pertaining to both embodiments of the control illustrated herein, is to provide a motor control unit including a diaphragm-operated motor control switch wired to a primary electrical connector which plugs into a suitable electric outlet, as well as a further electrical socket connected in series with such connector and switch, into which the usual plug connector of an existing sump pump motor may be plugged in the event the control is furnished as an adapter.

In an adaptation of the principles to the flood control of buildings in the event of overloading of a municipal or other sewer system, or its equivalent, the improved control is structurally very compact, simple, inexpensive and readily installed in or removed from a drain and clean-out riser by an unskilled person. As installed in a rural building or other setting not associated with a sewer system, the apparatus of the invention also eliminates the need for a relatively large sump and sump pump, and the expense, danger and odor incident to their use. Its units may be installed in a sub-floor collector riser constituted by a four inch pipe.

It is a general object of the invention, as so embodied, to provide an improved floor control assembly featuring a self-contained and self-priming double pump unit including an above-floor pump adapted to be fitted to a basement floor clean-out opening of a plumbing system, preferably in association with an improved one-way back water control plug (as illustrated and described in my above identified application, Serial No. 684,308) positioned in the riser beneath the entrance of the usual storm drain line to the riser and trap. The pump is direct-driven by a motor positioned directly thereabove, under the control of the multiple diaphragm unit referred to, having its intake side in downward communication with the housing of a further primer pump disposed in the riser; and the diaphragm unit may be directly mounted on the above-floor structure, or otherwise. The above-floor pump is quickly primed by the sub-floor priming pump, eliminating an operational difficulty characteristic of existing generally comparable installations, which require that connecting hose be full before satisfactory operation is possible.

As distinguished from all other so-called self-priming pumps, it is not necessary to make any provision whatsoever in my improved pump to hold water or other liquid captive to a predetermined level at the intake side of the pump in order to prime it.

The foregoing as well as other objects will become more apparent as this description proceeds, especially when considered in connection with the accompanying drawings illustrating preferred embodiments of the invention, wherein:

FIG. 1 is a fragmentary view, partially broken away and in vertical section through a control unit or device in accordance with one embodiment of the invention in a sump pump;

FIG. 2 is a fragmentary view, in vertical axial section and partially broken away, of a pump unit and control of

the invention, as alternatively embodied in a rapid priming sewer flood control device; and

FIG. 3 is a fragmentary view in section similar to FIGS. 1 and 2, showing an improved means for inter-communicating certain chambers of the control unit for improved vacuum responsivity.

Referring first to an adaptation of the principles of the invention to a sump pump installation, generally designated 10, as illustrated in FIG. 1 of the drawings, a portion of a vertical motor shaft housing 11 is shown, with a motor driven shaft 12 projecting downwardly therein. Shaft 12 is secured to a centrifugal pump impeller 13 in an impeller housing 14 beneath the shaft housing. A conventional intake trap 15 is associated beneath the pump impeller housing 14 and the latter is provided with an upright discharge pipe or duct 17.

A diaphragm and switch housing or casing is generally designated 16, being constituted by four casing members 18, 19, 20 and 21 suitably secured together in coaxial relation. A primary flexible diaphragm 22 of suitable flexible material such as spring brass, treated fabric, or the like, is marginally clamped between members 18 and 19 to in part define a static pressure chamber 23 of small volume on its left and a vacuum chamber 24 on its right.

A suitable clamp member 25 is provided on the casing member 18, by which the control housing or casing 16 may be supported at a desired elevation on the pump discharge pipe 17.

The casing member 20 is in the form of an annular ring mounting a dual diaphragm unit 26 between the casing members 19, 20 on either side thereof. This diaphragm unit comprises a first or inner flexible diaphragm 27 and a second or outer similar diaphragm 28, both of material similar to that of the primary diaphragm 22. They are marginally clamped between the casing ring 20 and the respective casing members 19, 21, so as to coact with the ring in defining an air space or air pressure chamber 29 therebetween. Diaphragms 27, 28 are further maintained in fixedly spaced relation to one another by a short spacer sleeve 30 at their center, this part being clamped in place by an axial stud 31. The free end of stud 31 extends through an axial aperture 32 of substantial size in the adjacent face of casing member 19, for engagement by a contact disk 33 on primary diaphragm 22.

The inner peripheral wall 34 of the diaphragm spacing ring 20 is of outwardly tapered or frusto-conical outline, and it is seen that there is thus provided an air pressure chamber 29 in which the area, i.e., of effective, pressure-responsive flexibility, of the outer diaphragm 28 exposed to pressure is larger than the area of the inner diaphragm 27 similarly exposed.

Structural features of the dual diaphragm unit 26 are similar to what is illustrated and described in my Letters Patent 2,730,591 of January 10, 1956, and it can be seen that when pressure exists within the chamber 29 there is a resultant force to the right, as viewed in FIG. 1, tending to move the diaphragm unit in that direction, due to the force times area differential product. It is also seen that in using a pair of opposed diaphragms of different area it is possible to employ relatively large diaphragms, with resultant freedom of movement and avoidance of fatigue and the like. The actual difference in area between the diaphragms 27, 28 may be as little as required.

The small volume static pressure chamber 23 is downwardly communicated by a passage 36 with a hydrostatic pressure tube 37 of relatively large internal bore size, which tube terminates at a level adjacent but somewhat above the pump housing 14. This insures that the tube 37 will empty gravitationally after each pumping cycle, and not tend to build up a head therein after repeated frequent cycles, such as might affect the reliability of the control operation.

The vacuum chamber casing member 19 is bell-like in outline, and the inner diaphragm 27 of the dual dia-

phragm unit 26 coacts with it in defining the chamber 24, which it will be noted is of relatively large volumetric capacity as compared with vacuum chamber 23.

A vacuum line or tube 39 of small internal bore size, as compared with tube 37, extends downwardly from the chamber 24, being brought laterally at 40 into communication with the intake side of the impeller housing 14. The lateral tube length 40 extends into the trap 15 and is provided with an upturned end 41 coaxial with the intake eye of the impeller housing.

The air pressure chamber 29 between diaphragms 27, 28 is connected by a tube or pipe 43 with the upright pump discharge pipe or conduit, at a point 44 substantially below the connection at 45 of the tube 43 to the control housing or casing 16. Thus, entry of discharge liquid into the chamber 29, under the substantial pressure of pump discharge, is prevented.

An appropriate electrical control switch 47 is mounted within the space 48 between diaphragm 28 and the final casing member 21, which space is at atmospheric pressure. Switch 47 is a suitably enclosed, normally open type having a control button 49 positioned directly to the right of the center of the diaphragm 28, for actuation by the clamp stud 31 for the latter. The button may be a spring urged or the switch may be a reversible snap acting one, but, in accordance with the invention, switch 47 is one which will be actuated to close an electrical circuit only when a substantial force of, say 20 oz., is exerted on control button 49. Likewise, the switch 47 is chosen so that when this force drops to, say, 3 oz., the switch will return to its normally open condition.

Switch 47 is appropriately secured to a suitable U-shaped mounting bracket 51, to which a tubular horizontal mounting fitting 52 coaxially aligned with the switch control button 49 is in turn secured. The tube fitting 52 is threaded externally for rotative adjustment in a lateral boss 53 of casing member 21, and a nut 54 is applied to it to hold the fitting and switch rigidly in place when adjusted as desired.

Conventional wiring leads 56 are applied to the switch terminals and are brought outwardly of casing 16 through tubular fitting 52. The latter may be open at its outer end to maintain atmospheric pressure in casing chamber 48, or an atmospheric pressure port 52' may be formed in the casing member 21.

Thus it is seen that regulation of the control action may be accomplished by a rotative adjustment of the fitting 52 in casing boss 53, enabling the switch button 49 to be positioned variably in relation to diaphragm 28 and thus to regulate the commencement and duration of motor cycles.

In the sump pump unit illustrated in FIG. 1 the electrical leads 56 from the switch are brought out through the tubular mounting fitting 52, preferably in the form of a conventional insulated cable 58 leading to a conventional electrical plug-in connector 59, and a type of female electrical socket member 60 is connected in the cable 58 with its socket terminals 61 wired in series with the plug 59 and the terminals of switch 47. Cable 60 may be of any desired length, so that in applying the control unit as a replacement, all that is necessary to do is to connect the existing electrical motor connector (not shown) of the sump pump in the sockets 61, then plug the connector 59 in a suitable electrical outlet socket or box. It is then not necessary to make any particular mounting for the control casing or housing 16, and any support on which it may be suspended will suffice.

In the operation of the structure thus far described, it is evident that as the level of liquid rises predeterminedly in the respective hydrostatic pressure and vacuum lines 37, 39, the respective static pressure and vacuum chambers 23, 24 will be increasingly pressurized, although not in corresponding ratio. At the start of operation tube 37, being of relatively large bore, quickly compresses air in the relatively small pressure chamber, and tube

39, being of small bore, compresses air in the large vacuum chamber little or negligibly. Hence the opposition of hydrostatic pressures at starting has little retarding effect and may be disregarded.

Assuming that static pressure in tube 37 occasioned by a rise in level in the sump pressurizes chamber 23 sufficiently to cause the primary diaphragm 22 to engage the central stud 31 of dual diaphragm unit 26, and to cause the latter to engage and actuate the button 49 of switch 47, the pump motor is energized to operate impeller 13 and the sump liquid level falls accordingly, the vacuum tube 39 being subject as pumping goes on to the suction at the intake of the impeller.

The resultant partial vacuum becomes effective through vacuum tube 39 on chamber 24, and this vacuum causes the diaphragm structure to be held in closing relation to the switch 47. The vacuum is not reduced sufficiently to enable the diaphragm to move away from the switch button and permit the switch to open until the level has dropped beneath the intake, or impeller eye, end 41 of the vacuum line 39. When this occurs, the vacuum in chamber 24 is immediately broken, and switch 47 will open.

The provision of the vacuum line 39 is seen to constitute one of two available simple and convenient ways to materially lengthen the operating cycle of the motor, once it has been started, and thus practically dry out the sump before the motor cycle terminates.

The other control aspect of the improvement, present in both of the embodiments of the invention herein described, is in the holding of switch 47 closed by internal pressurization of the dual diaphragm unit 26, through tube 43, under the discharge pressure in pipe 17 as applied to the differential in area between the constituent diaphragms 27, 28 of that unit. As indicated above, this action is most effective when the installation is operating against a high hydraulic head, the discharge pressure differential being ample to keep switch 47 closed. The other or vacuum effect is better effective against a low head. In both instances initial starting is accomplished by hydrostatic pressure in tube or line 37, and the two effects in many instances take place concurrently.

Reference should now be made to FIG. 2 of the drawings, showing an alternative embodiment of the invention in an anti-flood sewer control installation. Inasmuch as the control provisions in this modification closely resemble, if not being identical to those of FIG. 1, corresponding reference numerals are employed to designate corresponding parts or relationship, and repeated description is dispensed with.

The reference numeral 64 generally designates an improved self-priming pump unit as installed in an upright sewer riser or standpipe 65, for example, as in a typical domestic installation. The usual storm drain or seepage line (not shown) opens to this riser somewhat above its trap (not shown) which discharges to the city sewer. The usual sanitary system of the installation, from tubs, sinks, toilets and the like, discharges to the sewer downstream of the trap.

On many occasions it is desirable to control and confine the rise of sewer liquid in riser 65 beneath such seepage line, as by the use of an expandible backwater control plug such as is illustrated and described in my copending application, Serial No. 684,308, identified above.

The pump unit 64 comprises a vertically elongated priming housing 66 of upwardly tapering, frusto-conical cross section. The upper opening of this housing threadedly receives a nipple-like tubular connector 67 of desired length, which has a mounting disk or plug 68 fixed thereon above the housing 66. Disk 68 threads into the usual cleanout opening of riser 65, normally occupied by a floor closure plug.

Tubular connector 67 is threaded at its upper end into an annular axial boss 69 of a special pump housing 70,

the boss 69 surrounding the intake eye 71 to a centrifugal impeller 72 in this housing. Impeller 72 has its hub 73 fixed on an elongated driveshaft 75 extending downwardly and coaxially through the primer housing 66. The latter may be of, say, 3½ inch maximum diameter for installation in a four inch pipe riser.

Pump housing 70 discharges laterally through a discharge pipe 77 to which the upright air pressure tube or line 43 of the control casing 16 is connected; and pipe 77 may be return-connected to the sanitary line, or it may be connected to discharge to the exterior of the dwelling or other building in question.

A centrifugal priming impeller 78 featuring a top shroud disk or plate 79 is secured to the shaft 75 adjacent the lower end thereof, within a downwardly tapered conical bottom portion 80 of primer housing 66. This end of the shaft may be appropriately journaled in a fixed intake trap 81 secured beneath housing 66, through which liquid enters to the blading of impeller 78 from the storm drain line therebeneath.

The upward divergence of the tapered lower housing portion 80 and the top shrouding of impeller 78 at 79 considerably assist the latter in obtaining a rapid initial lift of water, which is then further speeded to housing 70 by the upward convergence of the housing 66 above impeller 78.

It is the function of the impeller 78 to positively and rapidly prime the above-floor pump housing 70 through tubular connector 67, whenever any water collects in the riser, whether storm drainage or otherwise. In this the priming pump housing 66 serves the combined functions of an impeller housing and an accelerative discharge pipe to the housing 70.

A suitable axially acting, spring urged rotary seal 83 is interposed between the upper end of the discharge impeller hub 73 and a hollow top extension 84 of centrifugal pump housing 70, the seal preferably including a carbon seal disk 85 to contain upward flow at this point.

Drive shaft 75 is appropriately journaled by a ball bearing 86 in a cylindrical mounting block 87 upwardly of pump housing 70, and the upper end of shaft 75 is connected by an appropriate coupling 87' with the depending shaft 88 of an electric drive motor 89 for control by the switch 47. The switch is similar in all particulars to that of the first embodiment, hence requires no further description. Its electrical conduit 58 will not incorporate the optional socket 60 of FIG. 1.

The shaft sealing, bearing and coupling provisions just described are encased in a tubular motor mounting sheath 90, which is clamped about a motor boss 91 at its top and about the axial housing extension 84 at its bottom, a clamp for this purpose being designated 92.

The operation of the system of FIG. 2 is, in regard to the multiple diaphragm operation of switch 47, identical with that of the sump pump installation of FIG. 1, save for the fact that the hydrostatic and vacuum tubes 37, 39 are brought down to the priming impeller 78 rather than main pump impeller 72. However, in the broad sense of the invention the two types of tube connection are equivalents.

The improvement of FIG. 2 provides an entirely self-contained, self-priming flood control assembly of great compactness, rapidly and easily mounted in operative position by an entirely unskilled user. In a rural or similar non-sewer installation the danger, cost and annoyance of a sump system may be avoided by the system of FIG. 2.

Priming impeller 78 lifts water practically instantaneously to impeller 72, upon static pressurization of tube 37, to close switch 47. Thereafter, either the pressurization of the internal space 29 of the dual diaphragm unit 26 from discharge line 77, or the evacuation of vacuum chamber 24 through tube 39, or both, serve to keep the switch closed until the desired result is had, regardless of the hydraulic head which is involved.

It is to be emphasized that the essential purposes of the

priming impeller 78 and its shaped housing 66, delivering through a coaxial tube or conduit 67 to the intake of the main impeller 72, is to effect a rapid lift of the liquid to the main pump, which is the essentially efficient agency for pumping. A rapid lift in a comparatively high intervening housing section of tubular form is made possible, to a pump whose primary function is to produce an adequate output pressure and capacity.

Referring to FIG. 3 of the drawings, there is shown therein an alternative arrangement for controlling pressure within the chamber 48 of the housing section 21, and at the same time intensifying the vacuum control action of the unit. The modification shown in FIG. 3 is, of course, equally applicable to the embodiments of the invention shown in FIGS. 1 and 2.

In this alternative form, the only change in reference to what is shown in FIGS. 1 and 2 is a very simple one, consisting of the fact that the stud which secures the diaphragms 27 and 28 together, being specially designated 94, is provided with an internal axial bore 95 of very small diameter throughout its length. The stud 94 receives nuts 96, 97 to secure the diaphragms 27, 28 to spacer 30, and it projects to the left for mechanical engagement and actuation by the contact disk 33 of primary diaphragm 22. Its right hand end is engageable with the button 49 of switch 47.

The effect of the bore 95 of stud 94 is to communicate the secondary or vacuum chamber 24 with the chamber 48 in which switch 47 is disposed. As the result of this, the vacuum in chamber 24, acting on diaphragm 27 in a direction to shift the latter to the left, is at the same time effective in chamber 48 on the diaphragm 28, of larger exposed size than the diaphragm 27, to overcome the first mentioned vacuum effect and as a result urge the diaphragm unit 26 to the right, as viewed in FIG. 3.

Thus, the relatively slight effect of the vacuum on the diaphragm 27 in opposition to its effect on primary diaphragm 22 is overbalanced, and a differential in vacuum responsive force is added to the force of vacuum on primary diaphragm 22, the diaphragms 22 and 28 working in the same direction to hold switch 47 closed until pumping has been thoroughly completed. Of course, in a control equipped with the improvement of FIG. 3, the port or passage 52' in casing member 21 will be eliminated, and the chamber 48 will be sealed from atmospheric pressure.

What I claim as my invention is:

1. A control for a pump comprising a control unit including first and second flexible, pressure responsive devices having areas of effective flexibility facing and at least in part defining a vacuum chamber, and being movable in opposite directions in response to evacuation of said chamber, said second device having a further area of effective flexibility spaced from and facing oppositely of said vacuum chamber, means coacting with said second device in defining a sealed chamber on the side of said further area thereof remote from said vacuum chamber, and a control device actuatable by said devices in response to evacuation of said vacuum chamber, said control unit having means placing said vacuum and sealed chambers in communication with one another, thereby subjecting said second device to vacuum on both of its areas.

2. A control for a pump comprising a plural-diaphragm control unit including first and second flexible, pressure responsive diaphragm devices having areas of effective flexibility facing and at least in part defining a vacuum chamber, and being movable in opposite directions in response to evacuation of said chamber, said second diaphragm device having a further area of effective flexibility spaced from and of larger area than its area facing said chamber, means coacting with said second device in defining a sealed chamber on the side of said further area thereof remote from said vacuum chamber, and a control device actuatable by said diaphragm devices in response to evacuation of said vacuum chamber, said control unit

having means placing said vacuum and sealed chambers in communication with one another; thereby subjecting said second device to vacuum on both of its areas.

3. A control for a pump comprising a plural-diaphragm control unit including first and second flexible, pressure responsive diaphragm devices having areas of effective flexibility facing and at least in part defining a vacuum chamber, and being movable in opposite directions in response to evacuation of said chamber, the opposite sides of the first device at least partially defining a hydrostatic pressure chamber opposite said vacuum chamber, said second diaphragm device having a further area of effective flexibility spaced from and of larger area than its area facing said chamber, means coacting with said second device in defining a sealed chamber on the side of said further area thereof remote from said vacuum chamber, and a control device actuatable by said diaphragm devices in response to pressurization of said hydrostatic pressure chamber and evacuation of said vacuum chamber, said control unit having means placing said vacuum and sealed chambers in communication with one another, thereby subjecting said second device to vacuum on both of its areas.

4. A control for a pump comprising a plural-diaphragm control unit including first and second flexible, pressure responsive diaphragm devices having areas of effective flexibility facing and at least in part defining a vacuum chamber, and being movable in opposite directions in response to evacuation of said chamber, said second diaphragm device having a further area of effective flexibility spaced from and facing oppositely of said vacuum chamber, means coacting with said second device in defining a sealed chamber on the side of said further area thereof remote from said vacuum chamber, and a control device in said sealed chamber actuatable by said diaphragm devices in response to evacuation of said vacuum chamber, said control unit having means placing said vacuum and sealed chambers in communication with one another, thereby subjecting said second device to vacuum on both of its areas.

5. A control for a pump comprising a plural-diaphragm control unit including first and second flexible, pressure responsive diaphragm devices having areas of effective flexibility facing and at least in part defining a vacuum chamber, and being movable in opposite directions in response to evacuation of said chamber, the opposite sides of the first device at least partially defining a hydrostatic pressure chamber opposite said vacuum chamber, said second diaphragm device having a further area of effective flexibility spaced from and of larger area than its area facing said chamber, means coacting with said second device in defining a sealed chamber on the side of said further area thereof remote from said vacuum chamber, and a control device in said sealed chamber actuatable by said diaphragm devices in response to pressurization of said hydrostatic pressure chamber and evacuation of said vacuum chamber, said control unit having means placing said vacuum and sealed chambers in communication with one another, thereby subjecting said second device to vacuum on both of its areas.

6. A pump control in accordance with claim 5 in which said second diaphragm device comprises a pair of spaced flexible diaphragms at least partially defining therebetween a pressure chamber having a pressure transmitting connection in communication therewith.

7. A control for a motor driven pump, comprising fluid pressure responsive means including elements at least in part defining chambers including a first static pressure chamber, a second vacuum chamber, and a third pressure chamber, and pressure transmitting means connected to said three chambers and adapted to place the same respectively in fluid pressure communication with a hydrostatic pressure, with a partial vacuum, and with a hydrodynamic

pressure, said control unit further comprising a control device operated by said pressure responsive means.

8. A control in accordance with claim 7, in which said last named means comprises at least two vertically elongated tubes extending upwardly to said control.

9. A control for an electric motor driven pump, comprising pressure responsive means including a first flexible diaphragm at least in part defining chambers including a first static pressure chamber, and a pair of diaphragms at least in part defining a second vacuum chamber and a third pressure chamber, said elements being movably responsive to pressure changes in said chambers, pressure transmitting means connected to said three chambers and adapted to place the same respectively in fluid pressure communication with a hydrostatic pressure, with a partial vacuum, and with a hydrodynamic pressure, and a control device operable by said pressure responsive means as said diaphragms respond to change in pressure in said chambers.

10. A control in accordance with claim 9, in which said last named means comprises at least two vertically elongated tubes extending upwardly to said control.

11. A control for a sump or like pump, comprising a housing structure having a first flexible diaphragm therein coating therewith in defining a first hydrostatic pressure chamber, said chamber having means to communicate the same with, and subject said diaphragm to, a hydrostatic pressure, said housing structure having therein a control chamber and a control unit in said control chamber, a flexible diaphragm device separating said control chamber from said hydrostatic pressure chamber and coating with said housing structure to provide a second hydrodynamic pressure chamber therein, said last named chamber having means to communicate the same with a hydrodynamic pressure and thus subject said diaphragm device to said last named pressure, said diaphragm device being engageable by said first diaphragm upon hydrostatic pressure flexure of the latter and engaging said control unit to operate the same, said diaphragm device maintaining said last named engagement under hydrodynamic force in said second chamber.

12. A control for a sump or like pump, comprising a housing structure having a first flexible diaphragm therein coating therewith in defining a first hydrostatic pressure chamber, said chamber having means to communicate the same with, and subject said diaphragm to, a hydrostatic pressure, said housing structure having therein a control chamber and a control unit in said control chamber, a flexible diaphragm device including spaced, second and third flexible diaphragms separating said control chamber from said hydrostatic pressure chamber and coating with said housing structure to provide a second, hydrodynamic pressure chamber therein between said second and third diaphragms, said last named chamber having means to communicate the same with a hydrodynamic pressure and thus subject said second and third diaphragms of said diaphragm device to said last named pressure, said diaphragm device being engageable by said first diaphragm upon hydrostatic pressure flexure of the latter and engaging said control unit to operate the same, said diaphragm

device maintaining said last named engagement under hydrodynamic force in said second chamber.

13. A control for a sump or like pump, comprising a housing structure having a first flexible diaphragm therein coating therewith in defining a first hydrostatic pressure chamber, said chamber having means to communicate the same with, and subject said diaphragm to, a hydrostatic pressure, said housing structure having therein a control chamber and a control unit in said control chamber, a flexible diaphragm device including spaced, second and third flexible diaphragms separating said control chamber from said hydrostatic pressure chamber and coating with said housing structure to provide a second, hydrodynamic pressure chamber therein between said second and third diaphragms, said last named chamber having means to communicate the same with a hydrodynamic pressure and thus subject said second and third diaphragms of said diaphragm device to said last named pressure, one of said second and third diaphragms being of greater effective pressure responsive area than the other, said diaphragm device being engageable by said first diaphragm upon hydrostatic pressure flexure of the latter and engaging said control unit to operate the same, said diaphragm device maintaining said last named engagement under a differential in hydrodynamic force in said second chamber on said second and third diaphragms.

14. A control for a sump or like pump, comprising a housing structure having a first flexible diaphragm therein coating therewith in defining a first hydrostatic pressure chamber, said chamber having means to communicate the same with, and subject said diaphragm to, a hydrostatic pressure, said housing structure having therein a control chamber and a control unit in said control chamber, a flexible diaphragm device including spaced, second and third flexible diaphragms separating said control chamber from said hydrostatic pressure chamber and coating with said housing structure to provide a second, hydrodynamic pressure chamber therein between said second and third diaphragms, said last named chamber having means to communicate the same with a hydrodynamic pressure and thus subject said second and third diaphragms of said diaphragm device to said last named pressure, the diaphragm of said second and third diaphragms which is adjacent said control chamber being of greater effective pressure responsive area than the other, said diaphragm device being engageable by said first diaphragm upon hydrostatic pressure flexure of the latter and engaging said control unit to operate the same, said diaphragm device maintaining said last named engagement under a differential in hydrodynamic force in said second chamber on said second and third diaphragms.
